UNITED STATES PATENT OFFICE.

GEORGE L. RICE, OF CHICAGO, ILLINOIS, ASSIGNOR TO INTERNATIONAL HARVESTER COMPANY OF NEW JERSEY, A CORPORATION OF NEW JERSEY.

SPINNING-MACHINE.

1,260,453.

Specification of Letters Patent. Patented Mar. 26, 1918.

Application filed May 8, 1915. Serial No. 28,750.

To all whom it may concern:

Be it known that I, GEORGE L. RICE, a citizen of the United States, residing at Chicago, in the county of Cook and State of Illinois, have invented certain new and useful Improvements in Spinning-Machines, of which the following is a full, clear, and exact specification.

This invention relates to spinning machines for producing binder twine.

The roving gill type of spinning machine has been used many years for the spinning of soft and short fibers for commercial yarn. The roving gill spinner also has been used for spinning hard, coarse fibers into a single strand yarn, such as binder twine. The binder twine produced by this machine, while being even, is left in a rough and unfinished condition. A rough, unfinished twine is objectionable in many cases.

To obtain the best commercial results, binder twine should present a hard, smooth and glossy finish in addition to being even throughout its length.

It, therefore, is the main object of my invention to produce twine which, when spun, is not only even throughout its length, but at the same time has a hard, smooth and glossy finish.

This object is accomplished by providing and equipping a spinning machine with co-operating parts for producing twine adapted to meet all commercial requirements.

The invention is illustrated on the accompanying sheets of drawings, in which—

Figure 1 is a fragmentary side elevation, parts being in section, of a spinning machine of the roving gill type embodying my invention;

Fig. 2 is a fragmentary front elevation of the same spinning machine;

Fig. 3 is a side elevation of the combined condenser, nipper and smoother, which combined unit is located intermediate the rolls and the flier of the spinner;

Fig. 4 is a longitudinal sectional view showing the condenser, nipper dies and smoothing dies in cross section, and also their relation with the rolls of a spinning machine, a sliver being shown passing from between the rollers and being twisted into twine;

Fig. 5 is a detail sectional view of a spring-pressed plunger for holding the

upper nipper and smoothing dies against 55 their lower co-operating dies; and

Fig. 6 is a detail sectional view showing a frictional driving connection between the driving source and bobbin supporting member.

The various novel features of my invention will be apparent from the following description and drawings, and will be particularly pointed out in the appended claims.

In the regular roving frame the fiber is 65 drawn by the roller and twisted into twine between the flier and the roller, the twist in all cases being stopped by the drawing roller. I am well aware that there have been many attempts to put on a smoother 70 in the space between the flier and drawing roller, but these were simply for the purpose of smoothing the twine after it was formed, and did not prevent the twist from running back to the drawing roller. 75

In my arrangement the nipper is installed between the flier and the drawing roller, and the twine is formed between the flier and the nipper, the function of the drawing roller being to deliver the fiber in an un- 80 twisted state to the nipper, where the twine is made. To accomplish this it is necessary that at no time there should be sufficient strain on the fiber between the flier and nipper to cause the twist to pass through 85 the nipper to the roller, and this is accomplished by means of a tension on the bobbin drive, which makes the surface speed of the bobbin travel a little slower at all times than is necessary to take up the 90 amount of twine fed by the drawing roller, and any time too much slack accumulates between the nipper and the drawing roller, the bobbins will increase in speed until the 95 excess slack is taken up, which keeps practically a uniform pull on the twine at all times. Without some flexibility at this point it would be impossible to accomplish this.

With this understanding, attention is directed to the drawings, in which it will be noted that my invention is shown in connection with a spinning machine 10 of the roving gill type, having a frame 11, in which is mounted a driving gear 12, from which, through suitable gears 13, 14 and 15, the 105 roll 16 of the machine is driven. Fiber, in the form of a sliver 17, is fed between the roll 16 and the co-operating rolls 18 by the usual

toothed chain 19, which is actuated in any suitable manner. The rolls 18 are provided with bands 20 of suitable friction material, such as leather, for assisting in the feeding 5 of the sliver between said rolls 18 and the roll 16, which extend transversely across the machine. The rolls 18 are rotatably mounted in suitable arms 21, which are pivotally mounted to a frame member 22, the rolls 18 10 pressing against the roll 16 under the influence of their own weight.

Heretofore it has been customary to pass the sliver directly from between the rolls 16 and 18 to the fliers 23 for winding the twine 15 onto bobbins 24, which are rotated in the same direction with the fliers 23 but at a slower speed than said fliers. While it has been possible to spin a twine even throughout its length with this arrangement, it has 20 not been possible to give the twine a smooth, hard, glossy finish, which is not only desirable, but is absolutely necessary to give the best commercial results. To produce a twine which is not only even throughout its length, 25 but also which has a smooth, hard and glossy finish, I have provided in this spinning machine, intermediate the rollers 16 and 18 and the fliers 23, a series of finishing members 25, which members are secured to a suitable 30 transversely arranged support 26, said members being staggered thereon crosswise of the machine.

Each of these finishing members includes 35 a condenser 27, upper and lower nipper dies 28, and upper and lower smoothing dies 29, the condenser in each case being adjacent the coöperating rollers 16 and 18 to receive the sliver passing therefrom. From the condenser the sliver is passed between the nipper 40 dies 28, where the sliver is pinched for the purpose of spinning the sliver into twine, through the action of the fliers 23, the twist in the twine extending back to the nippers 28 and no farther. From the nipper dies 28 the 45 twine passes through the smoothing dies 29, where the twine is given a hard, smooth and glossy finish, and passes therefrom in the form of twine 30 to the fliers 23, from which it is wound into the bobbins 24.

50 It is to be noted, reference being had to Fig. 4 of the drawings, that the sliver continues to be such up to and including the point 31 of the nipper dies 28, where the sliver is pinched, thus preventing the twist 55 in the twine from extending farther backward toward the rollers 16 and 18. In other words, the sliver is twisted into twine at the point 31 of the nipper dies, the twine thus twisted being smoothed in the smoothing 60 dies 29. Were it not for the fact that the nipper dies are located adjacent the smoothing dies and intermediate the smoothing dies and the rollers 16 and 18, the twist in the 65 twine would extend way back to said rollers and the twine thus produced would not and

could not be as smooth as the twine produced by means of the nipper dies and smoothing dies coöperating with the rollers. The upper nipper die 28 and the upper smoothing die 29 are forced into and maintained in yieldable contact with the lower nipper and smoothing dies, respectively, by spring-pressed plungers 32, (see Fig. 5) which are mounted in threaded receptacles 33, the latter being adjustably mounted in 75 an arm 34 pivotally mounted at 35 to the main supporting portion 36 of the finishing members 25. The plungers 32 have a stem 36^a which passes through an opening in the upper part of the receptacle 33 and is limited in its downward movement by any suitable key or pin 37. By means of the springs 38 acting to force the plungers 32 against the upper nipper and smoothing dies, said dies are held in yieldable engagement with 85 their coöperating lower nipper and smoothing dies. To lock the arm 34 in proper position to cause the full force of the springs 38 to be exerted against the plungers 32 for holding the same against the upper nipper 90 and smoothing dies, I have provided a pivotal latch 39 which passes over a projection 40 of the arm 34 for the desired purpose, said latch having a hollow portion 41 in which is mounted a spring 42 for holding the 95 latch in locking position. When the latch 39 is withdrawn from the projection 40 of arm 34 against the tension of its spring 42, the arm 34, with its spring-pressed plunger, may be swung out of engagement with the 100 upper nipper and smoothing dies.

To place the bobbins properly in the machine and to permit the same to be removed therefrom, it is necessary to move the finishing members 25 out of their normal operative positions. To accomplish this I have pivotally mounted the support 26 for the finishing members 25 to one end of arms 43, the other end of said arms being pivotally mounted to a shaft 44 upon which the rollers 18 are mounted. Intermediate the ends of the arms 43 on each side of the machine is pivotally connected a link 45, in turn pivotally connected to an arm 46, which is integral with an arm 47 pivotally mounted 115 upon a rod 48, the arm 47 having at its end a weight 49. By means of this arrangement it is seen that the finishing members may be swung out of the path of movement of the bobbins 24, when they are being placed 120 in and removed from the machine, the swinging movement being transmitted through the arms 43, link 45 and arm 46, which latter arm is connected to rod 48 mounted in the frame support 22, the weight 125 49 counterbalancing the weight of the finishing members 26 in their raised position.

The fliers 23, which are mounted upon spindles 50, are driven in the usual manner through gears 51 mounted upon their lower 130

ends, which mesh with an integrally formed spur and bevel gear 52, the bevel gear portion meshing with another bevel gear 53, which receives its motion from the driving shaft 12 through suitable gears 54, 55, 56 and 57, the gears 55 and 56 being mounted upon the same shaft 58. The gears are so proportioned that the fliers 23 rotate at a greater speed than the bobbins 24, the bobbins being driven from gear 55 through gears 59 and 60, the latter being mounted upon a shaft 61, upon which shaft is a bevel gear 62 meshing with another integrally formed bevel and spur gear 63 which meshes with gears 64, each of which (see Fig. 6) is formed on a sleeve 65 which loosely surrounds the spindle 50. In each case, keyed to the sleeves 65 to rotate therewith, is a disk 66, which is separated from the bobbin carrying disk 67 loosely mounted on sleeve 65 by a circular disk of friction material 68, such as leather or any other suitable material, this friction disk being preferably simply placed between the disks 66 and 67 and secured to neither one, this disk 68 forming a slip or friction drive between the source of driving power and the bobbin 24, which is mounted upon the disk 67. The bobbin 24 is held upon the disk 67 in the usual way by the heads 69 of studs passing up into openings in the bobbin for the reception of said heads, whereby rotary movement is transmitted to the bobbin. The disk 66, which is keyed to the sleeve 65, is pressed toward the disk 67 and yieldingly held in engagement with the intermediate friction disk 68 by a flat spirally arranged spring 70 which engages a grooved portion in the disk 66 and rests against a suitably padded shoulder portion 71 on the sleeve 65. By means of this slip arrangement there may be a relative motion between the disks 66 and 67 to give the bobbin an increased speed to accommodate the more rapidly moving flier 23 under extreme conditions.

The nippers 28 having a pinching effect upon the sliver for determining the point of twist in the twine necessarily tend to hold the twine against the forward pulling movement of the fliers, which latter wind the twine on the bobbins. The fliers 23, however, are driven at a definite and relatively fixed velocity, thus drawing the twine from the nippers at a relatively high speed regardless of the strains placed on the twine. In view of the fact that the fliers 23 rotate at a speed considerably in excess of that of the bobbins 24, it is apparent that there is a great tension in the twine between the fliers and bobbins. The strain in the twine between the fliers and bobbins might be so great as to cause a break in the twine. This would be the case were it not for the slip or friction connection between the disks 66 and 67, or between the driving source for

the bobbins and the bobbins proper. In other words, when the tension in the twine becomes sufficiently great between the fliers and bobbins, the bobbins 24 will be given an increased speed to more nearly approach the speed of the fliers and thereby decrease or entirely release the extra strain placed upon the twine between the points in question. As stated above, this is made possible by means of the slip connection between the disks 66 and 67. This is of prime importance, especially where nippers are used for pinching the sliver and thus holding the twine to a greater extent against the action of the fliers.

The bobbins are given the usual reciprocatory motion for distributing the turns of twine on the bobbins, the reciprocatory action being transmitted to the bobbin supporting table 72, which is formed integral with a sleeve 73 slidably mounted upon a suitable vertically arranged stationary support 74. This sleeve 73 is provided with a rack 75, which is engaged by a pinion 76 which receives its forward and reverse motion from any suitable source. It will be noted that the gears 55, 59 and 60 are so arranged in the usual manner by pivotally mounted links 77 and 78 to permit a rising and falling of the bobbin support and still keep in mesh to transmit rotary motion to the bobbins.

By equipping this roving gill spinning machine with finishing means including the condenser 27, coöperating nipper dies 100 28, and coöperating smoothing dies 29, all intermediate the rolls 16 and 18 of the machine and the fliers 23, twine is produced which not only is even throughout its length, but which is given a smooth, hard and glossy finish which heretofore has not been accomplished by a machine of this type. By means of the slip connection between the bobbins and their driving source, undue tension in the twine 110 which might cause a breaking thereof is obviated; in other words, the slip connection permits the bobbins to take on an increased speed to more nearly approach the speed of the fliers under the direct influence of the 115 fliers, which transmits the excess speed to the bobbins through twine placed under excess tension. By means of the arrangement of the nipper and smoothing dies having spring-pressed plungers for pressing the upper dies in contact with the lower dies and a spring-pressed latch for holding said plungers in engagement with the upper dies, the sliver may be properly gripped at the 120 nipper dies to form a proper point of twist 125 and to prevent the twist from running way back to the rollers, and at the same time to give the twine a smooth, hard and glossy finish. Again, these finishing members, including the nipper and smoothing dies, 130

which are staggered along the transversely arranged support 26, may be swung out of their normal position and counterbalanced by the weighted arm 47 to permit the bobbin bins to be placed on and removed readily from the bobbin supports.

It is evident that there may be many modifications in the precise arrangement as herein particularly shown and described, and it 10 is my intention to cover all such modifications which do not involve a departure from the spirit and scope of my invention.

What I claim as new is:

1. In a twine spinning machine, the combination of an adjustably mounted nipper, means for positively feeding to said nipper a sliver of fiber of the proper size to produce twine of a desired tensile strength, and means for pulling the sliver through the nipper when in one position and twisting it 20 into twine after it passes through the nipper.

2. In a spinning machine, coöperating rollers between which a sliver passes, a flier, and pivotally mounted finishing means comprising a nipper and polisher interposed between said rollers and flier.

3. In a spinning machine, coöperating rollers between which a sliver passes, a flier, pivotally mounted finishing means comprising a nipper and polisher interposed between said rollers and flier, and means for counterbalancing said finishing means when swung from its normal position.

4. In a spinning machine, coöperating rolls between which a sliver may pass, a flier, pivotally mounted finishing means comprising a nipper and polisher between

said rolls and flier, and means for swinging said finishing means out of its normal position.

5. In a spinning machine, the combination of coöperating rollers between which a sliver is passed, one of said rollers being pivotally mounted, and a finishing member pivotally mounted on the shaft of said pivotally mounted roller.

6. In a spinning machine, the combination of coöperating rollers between which a sliver is passed, one of said rollers being pivotally mounted, a finishing member pivotally mounted on the shaft of said pivotally mounted roller, and means for counterbalancing said finishing means when it is swung from its normal position.

7. In a spinning machine, the combination of coöperating rollers between which a sliver passes, finishing means adjacent said rollers, and a link connection between said finishing means and the shaft of one of said rollers whereby the finishing means may be 60 swung out of its normal position.

8. In a spinning machine, the combination of coöperating rolls between which a sliver may pass, a bobbin upon which twine may be wound, finishing means between said rolls and bobbin which normally lies in the path of movement of said bobbin when it is being placed in and removed from the machine, and means for shifting the position of said finishing means to permit the bobbin 70 to be placed in and taken out of the machine.

In testimony whereof I affix my signature.

GEORGE L. RICE.
